BRUSH AND DISPENSING CABINET

Ezra Reed Lindsay, Salt Lake City, Utah

Application October 19, 1948, Serial No. 55,399

1 Claim. (Cl. 312—207)

1

This invention relates to a dispensing type cabinet and more particularly to a dispensing container which is adapted for holding a variety of articles and materials, such as tooth brushes, dentifrices, and/or analogous toilet articles. The invention is applicable to many uses, but it is particularly suitable for mounting on a wall or other supporting surface for holding toilet articles, for protecting them from unsanitary contact or conditions, and for dispensing bulk materials in small controllable quantities and without waste.

In the past, many types of racks, holders, and cabinets have been proposed and used for retaining toothbrushes, dentifrices, cream, paste, soap, and the like, and numerous such devices are used in homes, particularly in bathrooms, powder rooms, kitchens, and the like. It is obviously desirable that articles such as toothbrushes, used individually, be mounted separately and individually, and many types of racks have been proposed for this purpose. It is desirable that bulk materials, such as toothpowder, toothpaste, shaving cream, or lather soaps, and the like, be readily available, handy, and yet packaged so as to avoid spilling, dispensing of excessive quantities, access to moisture or loss of moisture, free contact with the air being usually objectionable with these latter materials.

Commercial tubes, cans, and the like, which are commonly provided for soaps, creams, dentifrices, and the like, are commonly designed for dispensing and are often but not always satisfactory. They are frequently deficient when they must be used by children or other persons who are inclined to be careless in their use. There appears to be need for a simple apparatus which will dispense measured quantities of powder, or controllable quantities of toothpaste, shaving soap, etc., without spilling. Such apparatus should be easily operated, firmly supported in a convenient location, and it should be constructed so as to preserve and keep clean and sanitary the various articles or products contained therein or held thereby.

Hence an object of the present invention is to provide an attractive, convenient holding cabinet or rack for toilet articles. A further object is to combine with such a holding cabinet or rack structure a simple and convenient dispensing apparatus for bulk products, preferably capable of dispensing both loose, pulverulent material and wet plastic or paste like material. A further object is to combine with a rack or holder for toilet articles or the like, means for metering or

2

dispensing uniform quantities of loose bulk material such as toothpowder, soap powder, or the like. Still another object is to combine with an article rack or holder a means for dispensing moist plastic bulk material, such as toothpaste, soft soap, or the like, in such a manner that the material is normally protected against undue exposure to the atmosphere with resultant excessive drying and/or hardening. It is desirable that such materials be quickly available when needed and this invention includes improved means both for protecting them and for dispensing them without waste.

Additional objects are to hold separate from each other and out of contact with dust or other unsanitary matter articles which are used individually such as toothbrushes and analogous toilet articles, to mount these in a manner that they are always identifiable and distinguishable though protected, to support the holding and dispensing mechanisms firmly and yet in a manner to permit easy and quick removal from a wall or other support, and in general to provide additional conveniences in an attractive structure of increased utility. Still other objects will become apparent as this description proceeds. Therefore, reference will next be had to the accompanying drawing, wherein

Fig. 1 is a top plan view of a preferred embodiment of this invention, parts being broken away to show the construction more clearly;

Fig. 2 is a front elevational view of the structure of Fig. 1, other parts being broken away in this figure to show additional details;

Fig. 3 is a detail view, with parts broken away, showing in particular the inner construction of means for dispensing loose pulverulent or granular material, such dispersing means forming a part of the invention;

Fig. 4 is a detail view of means for controlling and cutting off the flow of moist plastic material as dispensed from means shown at the left of Figs. 1 and 2;

Fig. 5 is a vertical sectional view with certain parts omitted taken substantially along the line 5—5 of Figs. 1 and 2, showing also a toilet article (toothbrush) in place in the holder with the bristles thereof protected from contact with other articles or foreign elements;

Fig. 6 is a detail view in elevation of a bracket for mounting the assembly of Figs. 1 and 2 on a suitable support such as a vertical wall surface;

Fig. 7 is a side elevational view of the same element, taken from the left of Fig. 6; and

Fig. 8 is a top plan view of the element of Figs.

6 and 7, showing fragmentarily the cabinet structure of this invention mounted thereon in a suitable fashion.

Referring first to Figs. 1 and 2, the structure comprises a hollow body member 10, formed for example by molding a suitable plastic material such as polystyrene, vinyl resin, methacrylate resin, phenol formaldehyde condensation resin or the like. The material used may be selected from a wide variety of sources, wood, metal, or glass being useful in lieu of plastic, if desired. It is advantageous, however, for some purposes, to use a material which is translucent, preferably transparent, so that articles and materials in the cabinet may be visible. This adds to the convenience and attractiveness of the structure, but is not always essential.

As shown, the body 10 is preferably of one-piece construction, but it may be made in several parts if desired. Unitary construction is normally preferred for simplicity and, as herein shown, the body 10 comprises a rear wall structure 11, a front wall structure 13, a bottom wall 15, and hollow cylindrical end members 17 and 19, respectively. The body 10 comprises a number of hollow sections or compartments 21, 23, 25, 27, and 29, in addition to the cylinders. These are preferably entirely separate from each other, though they may be only partially separated if desired. As shown in Fig. 1, partition elements 31, 33, 35 and 37 are provided between the compartments. The bottom wall 15 contains a series of openings 39 of a suitable size, one below and opposite each of the compartments 21, 23, etc. These are particularly useful when the device is designed to hold toothbrushes, these openings 39 being of such dimensions that the articles such as toothbrushes may be easily inserted but retained by the resistance of the bristles, for example.

The body member 10 is provided with a suitable cover 41, made preferably of the same material as the body 10, though a contrasting material may be used if desired. The cover 41 has a down-turned flange 43 formed integrally therewith and shaped to fit closely about the upper edge portion of the main body 10. The body may be formed with indentations between the hollowed sections and opposite some or all of the partitions 31, 33, 35 and 37. These are indicated at 51, 53, 55 and 57, respectively, on the front of Fig. 2. Corresponding indentations may be formed in the rear wall 11 of the body, as indicated at 61, 63, 65 and 67. The cover is preferably formed to fit closely into these indentations, although that is not always necessary.

To retain the cover in place, the front and rear wall members 11 and 13 of the body 10 are provided with detent means, such as the holes or indentations 71, 72, 73, and 74, respectively. The cover member has corresponding bosses 75 and 76 on the front flange portion 43. Similar elements 77 and 78 are provided on the rear flange portion of the cover. These frictionally engage the indentations 71, 72, 73 and 74 so as to retain the cover in place. By springing the flanges slightly, the lid may be removed, but the detent means normally hold it securely in place and prevent its accidental displacement. See especially Fig. 5.

The cabinet assembly, as previously indicated, includes means for dispensing pulverulent material, for example toothpowder, soap powder, or the like. As shown herein, such means may consist of a container 81, cylindrical in form, formed in the part 19 previously mentioned which is part

5 of the assembly. The cylindrical container 81, as best shown in Fig. 3, has an opening 83 of appropriate size in the bottom wall 15. A star wheel dispensing element 85 is rotatably mounted, being fixed to or integral with a vertical shaft member 87 which projects through a suitable opening 89 in the cover member 41 (Fig. 2). The upper part of the shaft 87 is preferably knurled as indicated at 91, so that it may be rotated with the fingers. A guard member 92 comprises a flat portion 93 which overlies a part of the star wheel 85, member 93 also comprising an up turned flange 94 which may be secured in any suitable manner, as by adhesive, to the inner wall of the cylindrical member 81. With this construction none of the contents of the container 81 will pass out through opening 83 except when the dispensing star wheel 85 is rotated by means of shaft 87.

20 A receiving cup 95 may be provided to catch powder dispensed from container 81. As shown in Fig. 2, the cup 95 is in the form of a shallow dish having a bottom 96, upturned circumferential side wall 97, and a pair of upstanding arms 98, preferably integral with side wall 97. Each 25 arm has a small lateral projection 99 thereon, adapted to engage in an opening 100 formed in a down turned skirt portion 101 of the cylindrical wall 19. One of these openings is shown in Fig. 3. The arms 98 are resilient so that they may be sprung toward each other for detaching the detent lugs 99 from openings 100.

30 Dispensing means are provided also for moist plastic material such as paste, shaving soap, or the like. As herein shown, these means comprise a hollow receptacle 102, formed in element 17 which preferably is integral with the front and rear wall members 11 and 13, the receptacle being of a suitable shape and capacity. In the embodiment shown, the member 102 is cylindrical and is fitted with a piston like plunger 103 which is vertically movable. Piston 103 has a stem 105 which projects through an opening 107 in the cover member 41.

35 At the bottom of the receptacle 102 an opening 111 is provided through the side wall 17 from 45 which the contents of the receptacle may be dispensed. The bottom wall 15 also is provided with a channel or recess 113 so that the contents may still be dispensed when the container is nearly empty.

40 In order to provide a clean cut off for the paste or other soft material dispensed from the container 102, it is desirable to provide some means for cutting off the body which emerges through opening 111. Such means, as shown herein, comprise a vertically slideable knife member 115 constrained for movement in a vertical plane by overhanging guide flange elements 117, one of which is shown in Fig. 2, the other being cut away to show the knife construction in the sectional view. See 45 Fig. 4. The knife is urged downwardly by means of a spring 119 which operates on a plunger 121 which is preferably integral with the knife. The plunger 121 projects upwardly from the upper surface of a laterally extending finger piece 123 which is also formed integrally with or rigidly attached to the knife member 115.

50 To use the paste or soap dispenser the operator raises the knife 115 by lifting finger piece 123 so as to expose the opening 111. At the same time 55 he presses down on the plunger or stem 105 so as to force the material through the opening. The elements 123 and 105 are preferably of such size and location that they may conveniently be operated simultaneously with one hand. When sufficient material has been forced out through the

opening 111 the knife 115 is released. A spring 119 mounted in a housing 120 formed in or attached to wall element 17 forces the knife down to cut off the feed and also to close the opening 111 and prevent evaporation or drying of the material in receptacle 102. It will be understood that the parts are so proportioned and fitted with such accuracy that the material may be dispensed with accurate control and is prevented from losing its moisture appreciably during storage.

For mounting the dispenser on a wall or like vertical support, bracket means may be provided which frictionally engage and securely hold the dispenser cabinet through cooperating means formed thereon. Such bracket means may comprise a pair of bracket elements such as the single element of Figs. 6, 7 and 8. As shown, the member 131 which is designed for attachment to a wall surface is provided with a T-section tongue 133 adapted to fit within opposed tapered flanges 135 formed integrally with or attached to the rear wall 11 of the dispenser or container 10. Brackets 131 may be formed with openings 137 for screws or other wall fastenings and may be permanently attached to the wall. The dispenser unit is attached by simply sliding the tapered flanges 135 over the tongue elements 133 of the pair of brackets 131, the relationship being as generally shown in dotted lines in Fig. 2. Fig. 8 shows in section how the flanges 135 overlie the tongue 133. The base of the T element is narrowest at its upper end and the space between the flange elements is arranged to correspond in dimensions so that the assembly fits snugly and tightly but may readily be removed by lifting firmly. The degree of taper should be such that the parts can be readily separated but will hold firmly against unintentional separation due to slight or moderate jarring.

From the foregoing, it is believed that the operation and construction of the improved device will be clear. Tooth brushes may be inserted in each of the compartments 21, 23, 25, 27, and 29. The number of compartments may be more or less as desired. Articles other than tooth brushes may be inserted instead. Because the wall 13 is preferably transparent it is easy to identify a particular brush, assuming they are different in type or color. By the holding means described the brush bristles are protected against dust and against accidental contact with means which might contaminate, but they are all mounted so that they may be dried after use by the circulation of air around them.

The powder dispenser 81, 83, etc., meters out a measured quantity of material with each passage of an arm of the star wheel 85 past the opening 83. Falling of additional powder through the opening is prevented by the shield 93. The dispensed powder falls into the detachable cup 95 which catches all of it and holds it. When tooth powder is dispensed the tooth brush may be dipped into the powder or, if desired, the cup may be detached, and may be rinsed and replaced after use.

The paste or moist soap dispenser 17 operates in the manner previously described. A suitable quantity of material, as measured by the length of the extruded portion, may be forced out through opening 111 by pressing on the plunger 70

head 105. The dispensed part is then cut off cleanly and the opening 111 is closed substantially air tight by releasing the finger piece 123 and permitting the spring 119 to force the knife down until the finger piece rests upon the upper ends of the guide flanges 117.

From the foregoing it will be understood that there have been combined in a novel structure and in a unitary device means for holding and dispensing toilet articles and materials in a manner that is clean and convenient. By the use of transparent materials the contents of all parts are plainly visible. Suitable plastic materials may be molded to form all the compartments 15 of the main body in a single piece and the other parts, preferably made of the same material, may be attached by suitable adhesive or by other fastenings. Thus the parts 93, 117, 120, and 135 may be molded integrally with the body or may 20 be attached after separate manufacture. The lid or cover 41 is preferably of one piece. The rotary metering device, star wheel 85 and its stem 87, may be made in one piece or two, and the same is true of the plunger 103 and its shaft 25 or stem 105.

It will be understood by those skilled in the art that various modifications may be made without departing from the spirit of this invention. Many uses other than those described also will be 30 apparent and it is not intended to limit the invention to the particular modification or the particular uses mentioned above except insofar as will be required by the limitations in the following claim.

35 What is claimed is:

In a device of the character described, the combination of a compartmented body member of plastic material, said body member comprising a substantially continuous outer wall member 40 and transverse partition elements integral therewith to form a pair of substantially identical cylindrical end compartments and a series of intermediate brush compartments of rectangular cross-section and an integral bottom wall 45 enclosing a portion only of each of said brush compartments so as to hold a brush or the like in a restricted opening, a unitary removable cover for said body adapted to fit said outer wall member closely and enclose the top part of 50 all said compartments, resilient detent means cooperating with each other on said body member and on said cover for holding said cover on said body member, and dispensing means in each of said end compartments.
